UNITED STATES PATENT OFFICE.

IRA E. FLETCHER AND WILLIAM J. MACLEAN, OF BROCKTON, MASSACHUSETTS, ASSIGNEES TO UNITED SHOE MACHINERY COMPANY, OF PATERSON, NEW JERSEY, A CORPORATION OF NEW JERSEY.

SEWING-MACHINE.

1,017,397.

Specification of Letters Patent. Patented Feb. 13, 1912.

Application filed March 31, 1905. Serial No. 253,089.

To all whom it may concern:

Be it known that we, IRA E. FLETCHER and WILLIAM J. MACLEAN, citizens of the United States, and residents of Brockton, in the county of Plymouth and State of Massachusetts, have invented an Improvement in Sewing-Machines, of which the following description, in connection with the accompanying drawings, is a specification, like letters on the drawings representing like parts.

Our invention consists in improvements in sewing machines, and while susceptible of more extensive application, is particularly intended for sole stitching machines which are employed for stitching the outer sole of a boot or shoe to the welt thereof.

In stitching the sole to the welt the practice is frequently followed of sinking the stitches beneath or flush with the surface of the welt, as by permitting the stitch loops to be drawn into a slit or channel, the lip of which partially or wholly conceals the stitching from view. Such a slit or channel is formed by causing the face of the welt, as the shoe is moved along the work rest to meet a stationary blade or cutting tool in advance of but in the path of the stitching mechanism, so that the subsequently formed stitch is drawn into the slit thus formed. This practice of sinking the stitches into the welt is carried out about the fore part or sole extension without materially affecting the strength of the stitching, but if that mode of stitching is employed in and about the shank of the shoe, it has been found that the cutting of the required slit or channel for the reception of the stitches in the relatively thin welt, so weakens the material beneath the loops that at this shank portion where the stitching is required to withstand the greatest strains, the shoe is materially weakened.

To avoid this objection, it has been customary to stitch a shoe about the sole extension upon one machine provided with a cutting tool of the character referred to and thus provide the sunken stitches, and then transfer the shoe to a second machine without such cutting tool for the stitching

of the shank, so that the latter when 50 stitched may have the thread loops drawn down upon the unbroken surface of the leather and thereby to secure the full available strength thereof.

Our invention, in the specific embodiment 55 thereof here illustrated, provides means for stitching the outer sole to the welt upon a single machine and by a single uninterrupted operation, while permitting the thread loops in certain parts of the stitch path, as, 60 for example, around the extension sole, to be drawn into a previously formed slit or channel and thereby rendered wholly or partially invisible but permitting the thread loops at other parts of the stitch path, as, 65 for example, in the shank portion of the shoe, to be drawn down upon the unbroken surface of the leather, as is usual. This is accomplished in the described embodiment 70 of my invention, by causing the slit or channel forming means to be thrown into operative engagement with the leather when the sinking of the stitching is desired, as about the sole extension, and to be withdrawn from such operative engagement when the 75 sinking of the stitches is no longer desired, as about the shank portion.

In the ordinary types of sole sewing machines mechanism is customarily provided for gaging the distance of the stitch from 80 the edge of the sole and for lengthening or shortening the stitch, so that the connecting stitches between the sole and welt shall be at a uniform distance from the edge of the sole about the fore part or sole extension, while 85 along the shank portion the stitches shall lie farther from the edge of the sole and have an increased length.

The described embodiment of our invention also comprehends connections between 90 the slit forming means and the thread gaging mechanism, whereby a change in the position of the stitching relatively to the edge of the sole, as it passes from the shank portion to the fore part, or the change in 95 the length of stitch, or both, will be accompanied by movement of the slit forming means to a position of engagement with the

face of the welt where it can act to form a slit or channel therein for the reception of the thread loops.

Our invention will be best understood by reference to the following description when taken in connection with the accompanying illustration of one specific embodiment thereof, while its scope will be more particularly pointed out in the appended claims.

In the drawings,—Figure 1 is a plan view of a portion of a sole sewing machine embodying our invention; Fig. 2 is a side elevation of the parts shown in Fig. 1; Fig. 3 is a front elevation of the work rest edge, guide and awl carrier shown in Fig. 1; Figs. 4 and 5 show in plan and front elevation respectively on an enlarged scale the details of the work rest and edge guide with the slit forming device swung out of its effective position; Figs. 6 and 7 show similar views to Figs. 4 and 5, respectively, with a slit forming device swung into its active or slit forming position, and Fig. 8 is a side elevation of the parts as shown in Fig. 4.

Our invention may be applied to any suitable form of sole sewing machine, and the functions thereof may be performed in a great variety of ways; but to illustrate in detail one embodiment of our invention we have shown the same as applied to a well-known form of sole sewing machine of the type illustrated in Patent No. 563,471, dated July 7, 1896. In a machine of this character the shoe is presented to the machine with the sole uppermost and the welt resting on the work rest *a*, along the upper horizontal face of which it is fed to bring the face of the welt within the path of suitable stitching mechanism. As illustrative of the stitching mechanism I have shown the curved awl *b* and the awl sector *b'*, in the position which they occupy relatively to the work rest *a*, further illustration of remaining details of this well-known stitch forming mechanism being unnecessary to an understanding of the present invention. The work rest *a* is provided with the usual slot through which the awl and needle work.

As the shoe is fed along the work rest, during the stitching of the sole extension or fore part, its position thereon and the distance of the stitching from the sole edge is regulated by the edge rest *c*, the face of which contacts with the outer edge of the sole and acts to locate the stitch with reference thereto. The edge rest *c*, as is usual in this class of machines, is carried upon a suitable slide, which may be moved by the lever *d*, pivoted at *d'* to withdraw the edge rest rearwardly away from the sole edge and away from the position shown in Fig. 1 or may be moved to cause it again to assume that position. When the edge rest is withdrawn from the position shown in Fig. 1 to some such position as is shown in Fig. 4,

which latter position is assumed during the stitching around the shank portion of the shoe, the outer edge *a'* of the work rest enters the crease of the shank and guides the boot or shoe in its travel along the rest there to properly position the stitches in the welt.

Rearward movement of the lever *d* and withdrawal of the edge rest *c* is effected when the shank portion leaves the work rest and the extension sole passes thereon, and this is ordinarily performed by the operator who throws the lever *d*, the said lever also acting through the handle *e* and its arm *e'* engaging the grooved stud *e''*, the latter secured to the awl support *b''*, to move the latter and the attached awl laterally and thereby shorten the stitches about the fore part of the shoe. This mechanism is well-known and requires no further description.

Referring now more particularly to Figs. 4 to 8: during the stitching of the sole extension, the face of the welt as it travels over the work rest *a*, and prior to its engagement by the stitch forming mechanism, is caused to meet an appropriate slit or channel forming device, which herein consists of the swinging blade carrier *f*, pivotally mounted in the slot in the work rest *a* and having the blade *f'* herein shaped to cut a comparatively thin, shallow slit or channel, into which the subsequently formed stitches are drawn. During stitching of the extension sole, the blade is held fixedly in its slit forming position shown in Figs. 6 and 7 by the projecting finger *c'*, which projects from the supporting arm of the edge rest outwardly and beneath the face of the work rest *a* to engage the heel *f''* of the swinging pivoted blade carrier.

The slit forming blade is held in its slit forming position, shown in Fig. 7, during the stitching of the fore part, and after the stitch loops are drawn down into the channel thus produced, the pressure of the raised lips *a''* upon the work rest, as the shoe is traversed, assisted by the tension of the thread, acts to lay down the lips or edges of the slit over upon the inserted thread loops.

When the fore part of the shoe has been stitched and the operator passes to the shank, he simultaneously throws the handle *e* to lengthen the stitch and withdraw the edge rest. The withdrawal of the edge rest also withdraws the finger *c'* from engagement with the heel *f''* of the blade carrier, so that the latter having no longer any support against the downward pressure of the leather upon the blade *f'*, swings back into the position shown in Figs. 4, 5, and 8, where the blade lies within the slot of the work rest and below the plane of the surface thereof. In this position the blade being no longer effective for cutting the advance slot, the stitches or loops are drawn down upon the

uncut surface of the leather and will so continue to be formed until the operator again moves the edge rest *c* forward and causes the engaging finger *c'* thereon to throw the 5 blade above the surface of the rest and into a position effective for cutting the necessary slit.

It will be obvious that while we have 10 illustrated our invention as applied to a sewing machine and in connection with one specific form of sole sewing machine and have illustrated the same by the details herein described, it will be understood that our invention is not limited to the mere details 15 which are shown for illustrative purposes to its application to any particular type of machine or for any particular purpose, but that many modifications in the same may be made and various applications thereof utilized without departing from its spirit..

Claims.

1. A sole sewing machine, having means for stitching the outer sole to the welt work feeding means and means for forming a 25 channel in the welt acting on the welt, in advance of the stitching means in line with the seam and movable into and out of engagement with the welt during the continued operation of the work feeding and stitching 30 means whereby the stitches may be sunk into the welt for a portion of the stitch path only.

2. A sole sewing machine, having means for stitching the outer sole to the welt work 35 feeding means and means for forming a channel in the welt acting on the welt in advance of the stitching means in line with the seam and movable into and out of engagement with the welt during the continued 40 operation of the work feeding and stitching means whereby the stitches may be sunk into the welt about the forepart of a shoe and drawn down upon the unbroken surface of the welt about the shank portion thereof.

45 3. In a sole sewing machine the combination with stitching mechanism, means acting in advance of said stitching mechanism to form a slit or channel in the leather, and means for throwing said slit forming means 50 in and out of engagement with the leather permitting a continued operation of the machine in sewing a seam.

4. In a sole sewing machine the combination with stitching mechanism of means for 55 gaging the distance of the stitch from the edge of the sole, means acting in advance of said stitching mechanism for forming a slit in the leather and means for throwing said slit forming mechanism into or out of engagement upon change in said gaging means.

5. In a sole sewing machine the combination with stitching mechanism, means for 60 changing the length of the stitch, means acting in advance of the stitching mecha-

nism for forming a slit in the face of the leather, and means for throwing said slit forming mechanism into and out of engagement upon change in said stitch changing mechanism.

6. In a sole sewing machine the combination with a work rest, a sole edge guide a cutting tool forming a slit in the leather traversing said work rest and means whereby the cutting tool is controlled in position by said edge guide.

7. The combination with a sole sewing machine of a slit forming member acting in advance of the stitching mechanism and movable from an operative to an inoperative position during the operation of sewing a seam.

8. In a leather sewing machine, the combination with a work rest and stitching mechanism, of a cutting member pivoted to said work rest in advance of the path of the stitching mechanism and movable about its pivot during the operation of sewing a seam from an operative to an inoperative position.

9. In a leather sewing machine the combination with stitching mechanism, of a movable channel cutting member adapted to act in advance of the stitching mechanism in line with the seam to cut a channel to receive the stitches, and means for throwing said cutting member into and out of operation permitting a continued operation of the machine in sewing a seam.

10. In a leather sewing machine the combination with stitching mechanism, of a slotted work rest and a blade carrying member pivotally mounted in the slot thereof and movable about its pivot to throw the blade into and out of operation.

11. In a leather sewing machine the combination with stitching mechanism, of a slotted work rest, a blade carrying member pivoted in the slot thereof and having a depending portion, and means for engaging with said depending portion to throw the blade of said blade carrying member above the face of the work rest.

12. In a leather sewing machine the combination with stitching mechanism, of cutting means for cutting a slit in advance of the stitch, said cutting means being adapted normally to be held in an inoperative position by contact with the leather, and means for throwing said cutting means into an 120 operative position.

13. A shoe-stitching machine, having, in combination with the stitching instrumentalities, a knife for cutting a channel in the welt of a shoe in advance of the operation of the stitching instrumentalities, and means for throwing the knife into and out of operative engagement with the welt during the continued operation of the machine in sewing a seam.

14. A shoe stitching machine, having, in combination with the stitching instrumentalities, a knife movable into and out of operative position for cutting a channel in the welt of a shoe in advance of the operation of the stitching instrumentalities, and means for moving the knife into operative position during the continued operation of the machine in sewing a seam.
15. A shoe stitching machine, having, in combination, with the stitching instrumentalities a work support provided with a surface to receive the welt of a shoe, a knife for cutting a channel in the welt in advance of the operation of the stitching instrumentalities, and means for projecting the knife above the welt supporting surface of the work support during the operation of the machine.
16. A shoe sewing machine, having, in combination, with the stitching instrumentalities, a work support, a knife mounted on said support and movable thereon into and out-of operative position for cutting a channel in the welt of a shoe in advance of the 25 operation of the stitching instrumentalities and means for moving the knife into operative position during the operation of the machine.

In testimony whereof, we have signed our 30 names to this specification, in the presence of two subscribing witnesses.
